(57) **CLAIM**

I claim the ornamental design for a reverse current blocking module for use in a solar power installation, substantially as shown and described.

DESCRIPTION

FIG. 1 is a perspective view of a reverse current blocking module for use in a solar power installation showing my new design;

FIG. 2 is a top plan view thereof;

FIG. 3 is a bottom plan view thereof;

FIG. 4 is a rear elevation view thereof;

FIG. 5 is a front elevation view thereof;

FIG. 6 is a right side view thereof; and,

FIG. 7 is a left side view thereof.

The features shown in broken lines in the various Figures are for illustrating environmental structure and form no part of the claimed design.
